CAN HANDLER

Pilade L. Vannucci, San Jose, Calif.

Application March 14, 1939, Serial No. 261,780

5 Claims. (Cl. 294—87)

The present invention relates particularly to a device adapted to pick up a number of cans at one time, and is for use in the same field as the device patented to me April 30, 1935, No. 1,999,491, entitled "Can handler."

In a device of the character above indicated it is of paramount importance that the weight be reduced as much as possible because it must be lifted in its entirety with every group of cans, and where one group after another is picked up all day long the weight of the device becomes a serious matter. Again, where a device is in more or less continuous use over a long period of time it is highly desirable that the number of moving parts be reduced to a minimum so that little or no looseness will develop through constant use that will interfere with its positive action.

It is, therefore, one object of the present invention to provide a can handler that, when placed in position will positively grasp the cans with but little mechanical movement of its parts.

It is another object of the invention to provide a device of the character indicated that will consist of but few and simple parts, that will be light in weight, positive in action, simple in form and construction, strong and durable, and highly efficient in its practical application.

In the drawing:

Figure 1 is a plan view of a device embodying my invention, a part being broken away.

Figure 2 is a side elevation of the same.

Figure 3 is a top plan view of a portion of another embodiment of the invention, a part being broken away.

In the particular embodiment of the invention herein disclosed I show at 1 a flat plate having two pairs of upstanding ears as 2 and 3 formed thereon adjacent its ends and paralleling its longer sides.

On the ears 2 is fixedly mounted a handle 4, and on ears 3 a handle 5 is pivotally mounted as shown at 6. The side bars of the handle 5 extend below the pivotal mounting 6 as indicated at 7 and are connected by a cross-bar 8 for the purpose hereinafter set forth. The handles are in parallel relation to each other and handle 5 may be swung toward or away from the other about its pivots 6.

The device as herein disclosed is designed to handle eight cans at one time, therefore six lugs as 9, 9a, 9b, 9c, 9d, 9e are formed thereon on the side opposite to the handles. These lugs are disposed with their outer sides flush with the sides of the plate, one at each corner and one at the center of each longer side. The inner

sides of these lugs are arcuate in form to engage the cans as shown, the corner lugs each engaging one can and the center lugs 9b and 9c each engaging two cans.

At 10 is shown a shaft journaled in plate 1 and passing vertically therethrough at a point centering upon the central space defined by four cans as 11, 11a, 11b, 11c.

Fixedly mounted on the shaft 10 and on the under side of the plate 1 is a conical member 12 forming four identical arms as at 13, 13a, 13b, 13c. Each arm has an arcuate top edge as 14, 14a, 14b, 14c concentric with the can against which it operates when in an operative position. On the upper end of shaft 10 is mounted an arm 15 pivotally connected as at 16 to a link 17. One end of link 17 has an upstanding part 18 provided with a slot 19 engaging rod or cross-bar 8.

When the handle 5 is in the position shown the arms 13 to 13c are disengaged from the cans, but when the handle is swung in the direction indicated by arrow 20 it operates to rotate shaft 10 and to thereby bring the arcuate face of each arm into contact with the facing can and to press the can against the arcuate face of the lug opposed thereto. By this means the four cans are so held that they may be lifted in a body and placed in any desired position, and then released by moving the handle back to its original position.

The above described can engaging device is duplicated to lift the other four cans, shaft 21 operating a conical member 22 identical with member 12 and operated by an arm 23 pivotally connected at 24 to link 17.

The member 12 may assume many different forms. For instance it may be a disc formed as shown at 25 in Figure 3. In this case turning the shaft 10 in the direction indicated by arrow 26 moves the cam edges 27 against the cans.

In this device, the rotative movement of the member 12, whatever specific form it may have, is of the utmost importance, because it permits reduction in the number of moving parts to a minimum with the advantages hereinbefore set forth, and effects positive engagement and disengagement with the cans with but little movement of the handle or lever 5.

It is to be understood that all of the can-engaging parts such as the lugs 9 and members 12 are formed to pass under the beads 28 on the can ends.

Although a certain specific embodiment of the invention has been illustrated and described, it will be understood that various alterations in

the details of construction and mode of assembly and operation may be made without departing from the scope of the invention as indicated in the appended claims.

5. I claim:

1. A can handler comprising, in combination, a body member adapted to overlie a group of cans and having can engaging devices disposed on one side thereof and spaced to engage the outer sides of a group of cans, an element rotatably mounted on the member and insertable in the space between the group of cans and movable into and out of engagement with the cans, and means operable to rotate said element into lifting engagement with the cans and urge the same into lifting engagement with the first mentioned can engaging devices.
2. A can handler comprising, in combination, a body member adapted to overlie a group of four contiguously disposed cans and having can engaging means fixedly disposed on one side thereof to engage the outer side of said group at four equally spaced points, rotatable means associated with the member and insertable in the space between the group of cans, said rotatable means having portions simultaneously movable into and out of engagement with the cans at points diametrically opposite the fixed can engaging means.
3. A can handler comprising, in combination, a body member adapted to overlie a group of cans and having can engaging means fixedly disposed on one side thereof to engage the outer sides of a group of cans, rotatable means associated with the member and insertable in the space between the group of cans in vertical relation to the body member, and means operable to rotate said last mentioned means into lifting engagement with the cans and to urge the cans

into lifting engagement with the first mentioned means, and comprising a handle fixedly mounted on the member on one side of its center, a second handle pivotally mounted on the member on the other side of its center and having an extension to form a lever, a link pivotally connected to the extension, and an arm pivotally connected to the link and fixedly connected to the rotatable means whereby a pivotal movement of the handle in either direction will impart a corresponding 10 rotary movement to the rotatable means.

4. A can handler comprising, in combination, a body member adapted to overlie a group of cans and having can engaging devices depending therefrom and spaced to engage the outer sides 15 of a group of cans, an element journaled in the member to center in the central space defined by the group of cans in opposed relation to said devices, said element having a peripheral surface formed into arcuate segments disposed in concentric relation with the cans when moved into engagement therewith, and means associated with the member operative to rotate the element into or out of engagement with the cans.

5. A can handler comprising, in combination, 25 a body member adapted to overlie a group of cans and having can engaging devices depending therefrom and spaced to engage the outer sides 30 of a group of cans, a shaft rotatably mounted in the member at a point centered upon the central space defined by the cans and projecting through said member into said space, an element fixedly mounted on said projecting portion of the shaft having a peripheral surface formed to engage the adjacent surfaces of the cans, and 35 means operative to rotate the element into or out of engagement with the cans.

PILADE L. VANNUCCI.
